UNITED STATES PATENT OFFICE.

MAX C. ROSENFELD, OF BOSTON, MASSACHUSETTS.

AERIAL TORPEDO.

1,324,928.

Specification of Letters Patent. Patented Dec. 16, 1919.

Application filed May 8, 1918. Serial No. 233,316.

To all whom it may concern:

Be it known that I, MAX C. ROSENFELD, a citizen of the United States, residing at Boston, in the county of Suffolk and State 5 of Massachusetts, have invented new and useful Improvements in Aerial Torpedoes, of which the following is a specification.

This invention relates to aerial torpedoes.

The object of the invention is to provide 10 an explosive shell with means to propel the same through the air a certain distance, said shell being provided with means to detonate the same after it has traveled a predetermined distance, or upon colliding with another body.

The invention also contemplates means for guiding the shell in its passage through the air.

The invention consists in the combination 20 and arrangement of parts set forth in the following specification and particularly pointed out in the claim thereof.

Referring to the drawings:

Figure 1 is a plan view of an aerial torpedo embodying my invention, a portion of 25 the supporting and guiding plane being broken away.

Fig. 2 is a sectional elevation of the same taken on line 2—2 of Fig. 1.

Fig. 3 is a front elevation of the same.

Like numerals refer to like parts throughout the several views of the drawings.

In the drawings, 5 is an explosive shell 35 consisting of a casing 6 filled with explosive material 7, said shell being cylindrical in form and having a pointed end or nose 8. A propeller 9 is located at the front end of the shell and is fastened to a shaft 10 by which it is rotated, said shaft being rotatably mounted in a bearing 11 at the front 40 end of the shell and in a cap 12 at the rear end of the shell. A tube 13 surrounds the shaft 10 within the casing 6 and to the rear end of the shell is fastened an auxiliary casing 14 which incloses an internal combustion engine 15. A tank 16 is mounted upon the top of the shell and is connected by a pipe 16' to the carburetor of the engine.

A time fuse 17 is fastened in a suitable 50 position, as, for example to the casing and consists of a suitable timing device including a clock mechanism which operates at a certain definite time to release a pin which strikes a cap 18 and explodes the charge 55 within the shell.

A guiding and supporting plane 19 ex-

tends over the top of the shell and is attached thereto by stay rods 20 and 21. The stay rods 21 are provided with turnbuckles 22 whereby they may be shortened or lengthened to lower or raise, respectively, the rear end of the plane 19.

A rudder 23 is pivoted at 24 to the auxiliary casing 14 and is adjusted thereon at different angles by means of an arm 25 pivoted at 26 to said rudder and fastened by a bolt 27 to the auxiliary casing 14, said bolt extending through a slot 28 provided in said arm.

Beneath the shell 5 and attached thereto 70 is a truck 29 consisting of a framework formed of vertical rods 30 and longitudinally extending horizontal rods 31. Upon said frame are journaled shafts 32 and 33 and upon these shafts are mounted wheels 75 34 and 35. The shaft 32 has weights 36 adjustably mounted thereon and the horizontally extending members 31 of the frame have weights 37 slidably mounted thereon. The weights 36 can be adjusted longitudinally 80 of the shaft 32 and thus balance the torpedo laterally thereof, while the weights 37 can be adjusted upon the longitudinal members 31 of the frame to balance the torpedo longitudinally thereof.

The general operation of the mechanism hereinbefore specifically described is as follows: The plane 19 is set at the desired angle by lengthening or shortening the rods 21 by means of the turnbuckles 22. The torpedo 90 is balanced longitudinally thereof by means of the weights 37 and laterally thereof by means of the weights 36. The requisite amount of gasoline is placed in the tank 16, the engine is started in the usual manner, 95 thus rotating the shaft 10 and the propeller 9. When sufficient speed has been attained by the propeller the device is released and starts in the direction of the arrow, Fig. 2, rolling along the ground at first upon the 100 wheels 34 and 35 and gradually rising from the ground, due to the inclination of the plane 19. Enough gasoline is placed in the tank 16 to carry the torpedo the desired distance. When the gasoline has been consumed the torpedo falls toward the ground 105 and the shell explodes at the time for which the time fuse is set.

In addition to the time fuse 17, an impact fuse 38 is preferably provided, the same being fastened to the cap 12 in the rear of the shell. Said impact fuse is adapted to be 110

detonated when the shell strikes another object or when it strikes the ground so that in case the time fuse 17 fails to operate or does not operate immediately upon the torpedo 5 striking the ground or a building or other object, the impact fuse 38 will operate to explode the shell.

Having thus described my invention, what I claim and desire by Letters Patent to set 10 cure is:

An aerial torpedo having, in combination, an explosive shell, means to detonate said shell after a predetermined definite interval of time, said means including a clock mechanism, an impact fuse adapted to detonate said shell upon collision with another body, a propeller at one end of said shell, an internal combustion engine located at the op- 15

posite end of said shell, the shaft of said engine extending longitudinally through 20 said shell and being fast at its front end to said propeller, a plane located above said shell adapted to support said shell in the air, means to adjust the inclination of said plane, a truck frame located beneath said shell, wheels journaled on said truck frame and means to balance said shell, said means including weights adjustable laterally and longitudinally on said truck frame. 25

In testimony whereof I have hereunto set 30 my hand in presence of two subscribing witnesses.

MAX C. ROSENFELD.

Witnesses:

CHARLES S. GOODING,
SYDNEY E. TAFT.
